UNITED STATES PATENT OFFICE.

JAMES ALBERT PECKHAM, OF SAN JOSE, CALIFORNIA.

SHOE-POLISHER.

1,257,736.

Specification of Letters Patent. Patented Feb. 26, 1918.

Application filed June 26, 1917. Serial No. 176,967.

To all whom it may concern:

Be it known that I, JAMES ALBERT PECKHAM, a citizen of the United States, residing at San Jose, in the county of Santa Clara and State of California, have invented new and useful Improvements in Shoe-Polishers, of which the following is a specification.

The object of the present invention is to provide a device for polishing shoes which will be simple in construction, effective in 10 operation, and convenient in use.

In the accompanying drawing, Figure 1 is a broken perspective view of my improved shoe polishing device; Figs. 2, 3, and 4 are 15 similar views illustrating various modes of using the device.

Referring to the drawing, 1 indicates standards mounted upon a suitable base 2, by dropping into auger holes which may be 20 in the top of a box or any other suitable support. Secured on the upper ends of the standards by nuts 3 are the terminal portions of a round rod or shaft 4. Mounted on said shaft 4 between said standards are a 25 central roller 5, which forms a foot rest, and terminal rollers 6, all preferably of wood.

A person using this device places his foot upon the central roller 5. For polishing the toe and front portion of the shoe, the operator 30 passes the polishing cloth 7 over its front portion and beneath the two terminal rollers 6, grasping the ends of said cloth with the hands, as shown in Fig. 2, then, by pulling first with one hand and then with the 35 other upon the cloth, he imparts a reciprocating motion to the cloth over the shoe top, thereby polishing the same. To polish the heel portion of the shoe, he passes the central portion of the polishing cloth around said 40 heel portion, and its terminal portions forwardly around the terminal rollers 6, as shown in Fig. 3, and then, by an operation similar to that described for polishing the toe portion of the shoe, he draws the polishing cloth backward and forward over the 45 heel portion. Fig. 4 illustrates the mode of

using the device when polishing the side portions and instep of the shoe. In doing this, one terminal portion of the polishing cloth is passed under heel and entirely around the 50 instep of the shoe, and a reciprocating movement is imparted to the cloth in the usual manner.

It will thus be seen that I have provided a device for polishing shoes which is simple 55 in construction, effective in use, since all parts of the shoe can be polished thereby, and convenient in operation, since it is in no case necessary that both hands be moved simultaneously close to the surface of the 60 shoe, or that the shoe be touched by hands at all.

I claim:—

1. In a shoe polisher, the combination of a shaft, rollers on the terminal portions of 65 the shaft spaced apart sufficiently to permit of a foot being supported in its normal position by a portion of said shaft between said roller, and means for supporting the ends of the shaft, the intermediate portions thereof 70 being free from any supporting means.

2. A foot rest, rollers on opposite ends thereof extending transversely to the foot when the latter is supported upon the foot rest transversely thereto, said rollers having 75 smooth surfaces, and the space immediately beneath the under sides of said rollers being free from obstructions.

3. In a shoe polisher, a horizontal shaft, three rollers respectively around a mediate 80 and terminal portions of the shaft, a base, and posts on said base for supporting said shaft wholly outside said rollers the terminal rollers having smooth outer surfaces adapted to permit a polishing cloth to be re- 85 ciprocated thereover in contact therewith.

4. A shaft, a foot rest carried by the middle portion thereof, rollers upon the terminal portions of the shaft, and standards for supporting the ends of the shaft.

JAMES ALBERT PECKHAM.
